Thomas Dowling*

UNITED STATES PATENT OFFICE.

THOMAS DOWLING, OF SALEM, MASSACHUSETTS.

IMPROVEMENT IN HOT-AIR REGISTERS.

Specification forming part of Letters Patent No. 37,388, dated January 6, 1863.

To all whom it may concern:

Be it known that I, THOMAS DOWLING, of Salem, in the county of Essex and State of Massachusetts, have invented a new and Improved Register for Hot-Air Furnaces; and I do hereby declare that the following is a full and exact description of the same, reference being had to the drawings accompanying this specification, and to the letters of reference marked thereon.

The nature of my invention consists in making a register to be placed within a floor with a cold-air passage arranged concentrically around it, and communicating with the hot-air passage, as hereinafter described, the same being for the purpose of avoiding the danger from fire near the floor, and dispensing with the use of the ordinary soapstone for a guard, usually inserted within the floor and made to receive the register.

It also consists in arranging a series of tubes in the hot-air pipe, so that they may be drawn up or down telescopically, for the purpose of drawing the hot air from the furnace when it does not come up readily.

To enable others skilled in the art to make and use my invention, I will proceed to describe the same, reference being had to the drawings accompanying this specification, in which is represented a register applied to the hot-air pipe of a furnace with the tubes composing the extension-pipes drawn up, as they are required to be in use.

I construct a register by making a circular case, A, rather more than twice as large as the outlet-pipe B, which comes up through the bottom of this case A, and extends upward therefrom about two-thirds of the length of this case. The top of this case is level with the floor C, and may be secured there in any proper manner, either by being screwed into the floor or by a flange turned over at the top, in which way I prefer to secure it. Around the top of this case I place a cast-iron collar, D, which is provided with suitable perforations E E E. On the inner edge of this collar is secured the top of the pipe F, which is a little more than half as long as the case A. By this pipe an annular space is made between it and the case A. Sliding into the

tube F is placed the tubes H and I. The top tube, I, is surmounted with a register, J.

The object of the tube F, in combination with the case A, is to make a space through which the cold air, by means of the perforations E E E, may pass down into the body of the register, and up with the hot air. The arrows show the direction of the current.

The object of the arrangement of the sliding tubes H and I is to cause a draft of hot air from the furnace to ascend more freely in places where from various reasons it does not come up as fast as is necessary to warm the room. This register may be set without a soapstone guard with entire safety from fire; and by this arrangement a better circulation of air is made in the apartment, and it is warmed more equally, because the cold air which is pressed down near the floor of the apartment and readily passes down through the apertures E to be warmed by the current of hot air from the furnace, and this process being continually repeated the room is warmed quicker than in the usual way. If it is desirable a damper may be placed in the horizontal part of the hot-air pipe B, and the rod connecting the damper may be passed up through the ring of the register, and the supply of hot air controlled in that way; but for general purposes the register in the top of the pipe I will be found amply sufficient. The upright tubes may be made so as to fit friction tight, or may be held up with a spring or catch in any suitable manner.

I make no special claim to the use of these tubes, but simply to the arrangement of sliding them up and down, so that when not in use they may be out of sight. Two or more of these tubes may be used, as is desirable.

Having thus fully described the nature of my invention, what I claim as new, and desire to secure by Letters Patent, is—

1. The combination and arrangement, substantially as described, of the case A, the tube F, and the perforated collar D, with the floor C and its register J, and the hot-air inlet-pipe B, whereby one or more air-passages are so formed between the floor and the hot-air pipe B as to cause, while hot air may be flowing out of the pipe B, and from thence

through the register, a current of cool air to flow downward through the collar D and the passage between the case A and the tube F, and thence upward through the said tube F and the register, and commingle with the heated air discharged from the pipe B.

2. The combination of one or more telescopic tubes, H I, with the register d, the

case A, the tube F, and the inlet-pipe B, the whole being so as to operate substantially as described.

THOMAS DOWLING.
